BY DIRECT AND MESNE ASSIGNMENTS, TO GARDNER FREEZER CORPORATION, OF
LANCASTER, OHIO

ICE CREAM FREEZER

Application filed December 14, 1928. Serial No. 325,996.

This invention relates to ice cream freezers, and particularly to freezers comprising a rotative drum, one face of which is refrigerated and another face of which is in contact with the mixture to be frozen, said mixture forming, through rotation of the drum, a more or less thin layer of ice cream upon the last mentioned face adapted to be removed by a scraper or other suitable means.

10 An object of the invention is to adapt a receiver for the ice cream scrapings to be also utilized as a channel for delivering an ice-cream-forming liquid into the casing of the freezer.

15 Another object is to establish an improved mounting in such casing of said receiver so as to facilitate its removal and replacement.

A further object is to provide a scraper for removing a layer of ice cream from the 20 surface of a revolving drum and to adapt said scraper for a further use in packing the scrapings in a suitable receiver.

Still another object is to provide a drum for receiving a suitable freezing mixture and 25 to provide in an improved manner for journaling said drum for quick removal from and replacement in the casing of a freezer.

A still further object is to provide in one 30 end of such a drum an opening for introducing a freezing mixture into the drum and to provide an improved means for quickly establishing a closure for said opening in sealing engagement with the drum.

It is also an object of the invention to provide in the casing of a freezer of the 35 aforesaid character a window permitting a visual inspection of the scrapings receiver so that it may be readily ascertained when said receiver is full.

40 These and various other objects the invention attains by the construction hereinafter described and illustrated in the accompanying drawings, wherein:

Figure 1 is a view in longitudinal vertical 45 section of the improved freezer.

Figure 2 is a front view thereof, with the casing partially broken to disclose the closure for the end opening of the drum.

50 Figure 3 is a transverse vertical section taken upon the line 3—3 of Figure 2.

Figure 4 is a top plan view of the front end portion of the drum.

Figure 5 is a side view of said end of the drum.

Figure 6 is a fragmentary perspective view 55 of a bracket interiorly carried by the lower member of the casing for journaling an end of the drum.

Figure 7 is a fragmentary elevation in partial section of the journal for the front end 60 of the drum.

Figure 8 is a similar view of the rear journal of the drum.

Briefly referring first to the primary elements of the improved freezer, the reference 65 characters 1 and 2 designate upper and lower members of a casing, the former providing a cover for the latter, and the latter being adapted to receive in its lower portion a liquid ice cream mixture. In said casing is 70 journaled a drum 3, adapted to receive a freezing mixture such as ice and salt, the axis of said drum being preferably in the meeting plane of the upper and lower casing members, the lower portion of said drum being in use immersed in said ice cream mixture. A handle 4, or other suitable drive element for the drum, is carried thereby in an exterior relation to the casing. There is further arranged within the casing and preferably upon the upper member thereof, a scraper blade 5, normally positioned to engage the exterior face of the drum for substantially its entire length to remove a layer 75 of ice cream from said face. Finally the casing contains a receiver 6 mounted in such proximity to the drum and scraper as to receive the scrapings and preferably also in such a relation to the scraper that the latter 80 may be employed to pack the contents of said receiver.

One end of the drum 3 is closed and is centrally formed with a socket 7 for receiving a journal pin 8 integrally projecting from a bracket 9 which is interiorly attached to the member 2 of the casing at the upper edge of said member. The other extremity of the drum is formed centrally with an opening 10, providing for the introduction into and removal from the drum of 100

a freezing mixture. Marginally of said opening, a collar 11 projects outwardly from the drum, and within said collar an annular seat 12 for a closure 13 is provided. A pair 5 of lugs 14 radially projecting from said closure at opposite points thereof, are adapted to fit into a pair of recesses 15 in said collar to assure disposal of the closure in either of two positions. Centrally pivoted upon 10 the closure is a latch bar 16 which has its ends hooked as indicated at 17 and projecting sufficiently beyond said closure to engage an annular rib 18 formed as a radial projection upon the collar 11. To allow the hooked 15 ends of said latch bar to engage said rib the collar 11 is formed with a pair of diametrically opposed notches 19 through which the hooks 17 may pass as the closure 13 is inserted in said collar. When the closure is substantially seated, the bar 16 may be rotated 20 upon its central pivot to engage the hooks thereof with said rib and secure the closure in place. It is preferred to cam the face of the rib 18 adjacent to the drum 3 in each direction from the notches 19 so that regardless 25 of the direction in which the latch bar is rotated from its initial position of registration with said notches, the cam faces of said rib will tend to draw the closure firmly to its seat. Preferably a gasket 20 is interposed between the closure and its seat to assure a more perfect seal.

It is preferred to mount the crank handle 35 rigidly and centrally upon the closure 13 and to pivot the latch bar 16 upon said crank handle. Also it is preferred to form the inner or supporting portion of said crank handle with an annular shoulder 21 for engaging an opening 22, jointly formed in the 40 abutting edges of the casing members 1 and 2, for journaling the front end of the drum. A bushing 22a formed of rust-proof steel is preferably cast or otherwise rigidly mounted upon the journal portion of the crank handle, as is best seen in Figure 7, to avoid the tarnishing that tends to occur where two relatively moving aluminum surfaces make contact. It is preferred furthermore to allow 45 only a slight clearance between the drum and the bottom of the casing so that the portion of the mixture to be frozen, which underlies the drum, will have only a slight depth, adapting it to freeze quickly. The bottom 50 of the casing is curved upwardly at one side of the drum to merge into one end of the casing member 1 as indicated at 23, and preferably the clearance of the wall 23 from the drum is progressively and gradually increased as said wall extends to its upper 55 edge.

Within the casing at the opposite side of the drum is disposed the scraping blade 5, the same being preferably pivoted upon the member 1 as indicated at 25, and resting of

its own weight against the drum, at an upward inclination.

Below the blade 5, the casing interiorly carries the scrapings receiver 6, which is of substantially a trough shape, extending parallel to the drum axis and adjacent to the drum periphery. Said receiver is preferably open at one end and closed at its other, and is preferably supported only at its front end and entirely upon the front wall of the casing. Thus an opening 26 conforming to said receiver is formed jointly in the front walls of the members 1 and 2, into which opening said receiver snugly fits. To maintain the horizontal position in use of said receiver and restrain it normally from inward or outward sliding, an annular rib 27 projects outwardly from the receiver to seat against the front face of the casing, and one or more lugs 28 project downwardly from said receiver in such a spaced relation to said rib as to be interiorly engageable with the casing wall. The tendency of the receiver to tilt about its supporting front end is counteracted by the bearing afforded by the lugs 28 against the interior of the casing and that of the rib 27 exteriorly upon the casing. The described arrangement is such that by slightly lifting the receiver by means of a handle bar 29, exteriorly carried by its end face, the lugs 28 may be raised clear of the lower margin of the opening 26 permitting the receiver to be then freely withdrawn from the casing. When partially so withdrawn, the receiver may be inclined, as is indicated in dash lines in Figure 3, 100 forming a channel through which an ice-cream-forming liquid may be readily introduced into the bottom portion of the casing without removal of the cover member 1.

For holding the upper and lower members of the casing normally engaged, it is preferred to attach a pair of spring catches 30 interiorly to the ends of the member 1, said catches projecting downwardly to interiorly overlap the ends of the member 2, and being apertured to engage projections 31 upon the end walls of the member 2. Push pins 32 are carried by said spring catches and project through openings formed in the meeting edges of the members 1 and 2 to permit said catches to be sprung back to release them from said projections.

To permit the operator to readily ascertain whether or not the accumulation of ice cream in the receiver is sufficient to warrant the removal thereof, it is preferred to provide a window opening above said receiver in the member 1 of the casing and to fit in said opening a transparent closure 33, of glass or other suitable material.

In the operation of the described appliance a sufficient quantity of the ice-cream-forming liquid is introduced into the casing member 1 to fully immerse the lower portion of said casing, and from time to time in the opera-

tion of the machine this liquid may be replenished as becomes necessary. In introducing said liquid the receiver 6 will preferably be partially withdrawn from the casing 5 as shown in Figure 3, being tilted in such position as said figure indicates, the liquid then being poured into the member 1 through said receiver. The drum 3 is initially substantially filled with a suitable freezing mixture such 10 as broken ice and salt. The operator now gradually rotates the drum 3 in the direction of the arrow in Figure 1, and the ice-cream-forming liquid will soon become so chilled as to deposit a thin layer of ice cream upon 15 the outer face of said drum. The formation of this layer will primarily occur upon the bottom portion of the drum, since the portion of the liquid contacting with the drum bottom is relatively thin and will consequently 20 be more completely and rapidly chilled by the drum than other portions of the liquid.

This progressively formed frozen layer will be carried around by rotation of the drum until it encounters the scraper blade 5, being 25 removed by the latter and discharged into the receiver 6. Thus as the drum is rotated the scrapings of ice cream will continuously accumulate in the receiver 6, and from time to time may be packed down by the operator 30 by use of the scraper member 5 as is indicated in dash lines in Figure 1. To permit manipulation of the blade 5 so that it may serve both as a scraper and a packer a handle 34 is secured to the rear journal member of said 35 blade, exteriorly of the casing. The receiver 6 is removed when filled, and its contents discharged into some suitable receptacle and is then replaced for another filling.

The production of ice cream by this 40 proved freezer is accomplished rapidly and with very slight manual exertion, it being possible for a child to operate the freezer without difficulty. Apart from the bracket 9 and the blade 5 there are no interior projections upon the casing 1, 2 so that the latter may be easily and thoroughly cleaned.

Also the described provision for sealing the filling opening of the drum permits the closure 45 for said opening to be quickly sealed in place as to positively assure against any contamination of the ice cream by the contents of said drum.

The location of the drum completely within 50 the casing, as described, minimizes the access of atmospheric heat to the drum, and improves the appearance of the utensil.

While it will be apparent that the illustrated embodiment of our invention herein 55 disclosed is well calculated to adequately fulfill the objects and advantages primarily stated, it is to be understood that the invention is susceptible to variation, modification and change within the spirit and scope of the 60 subjoined claims.

What we claim is:

1. In an ice cream freezer, the combination with a vessel adapted to receive an ice-cream-forming liquid, of a rotatable member having a lower portion immersed in said liquid, a 70 scraper blade engaging the upper portion of said member for removing an adhering portion of the frozen liquid, a receiver for the scrapings removed by said blade, said blade being movable to pack said scrapings in said receiver.

2. In a freezer for ice cream and the like, the combination with a rotatable drum, of means for refrigerating one face of said drum, means for forming a frozen layer of liquid upon an opposite face of said drum, means for rotating the drum, a pivotal blade extending parallel to the axis of the drum and engaging the last-named face thereof for scraping off said layer, and a receiver for the scrapings removed by said blade, said blade being movable about its pivot into said receiver to pack the contents thereof.

3. An ice cream freezer comprising a casing adapted to receive in its lower portion a liquid to be frozen, a drum rotatable in said casing adapted to be immersed at its lower portion in said liquid, and further adapted to be interiorly refrigerated, means for rotating said drum, a blade exteriorly peripherally bearing upon said drum to scrape a frozen layer of said liquid therefrom, and a receiver for the scrapings removed by said blade, normally supported substantially horizontally below said blade, and adapted when partially withdrawn from the casing to assume an inclined position.

4. A freezer for ice cream and the like, comprising a casing, a drum rotatable in said casing, adapted to be interiorly refrigerated, a blade exteriorly peripherally engageable with said drum for removing a layer of frozen liquid therefrom, and a receiver normally supported within the casing in a position to receive the scrapings removed by said blade and adapted when partially withdrawn from the casing to receive in its withdrawn portion, a mixture to be frozen, and to discharge the same into the casing.

5. A freezer for ice cream and the like, comprising a casing adapted to receive a liquid to be frozen, a member rotatable in said casing adapted to be interiorly refrigerated, means for rotating said member, a scraper blade exteriorly engaged with said member for removing a frozen layer of said liquid therefrom, and a receiver for the scrapings removed by said blade, fitting into an opening in a wall of said casing and having a closed end forming a closure for said opening, the other end of said receiver being open.

6. In a freezer for ice cream and the like, the combination with a casing adapted to receive a liquid to be frozen and a drum rotatable in said casing adapted to be refrigerated,

of means for rotating said drum, a scraper blade exteriorly engaging said drum for removing a frozen layer of said liquid therefrom; and a receiver fitting in an opening in a wall of the casing and projecting into the casing for receiving the scrapings removed by said blade, said receiver being removable through said opening.

7. A freezer for ice cream and the like, comprising a casing, a drum rotatable in said casing, adapted to be interiorly refrigerated, said casing serving to receive a liquid adapted to form a frozen layer upon said drum through rotation of the drum, a receiver for the material comprising said layer, and means for removing said material from the drum and discharging it into said receiver, said receiver being adapted to assume a tilted position of partial withdrawal from the casing, adapting it for discharging into the casing the liquid to be frozen upon said drum.

8. In a freezer for ice cream and the like, a casing, a member journaled in said casing, a scraper bearing on said member, and a receiver mounted in said casing substantially below said scraper to receive scrapings removed from said journaled member, said casing having an opening in one wall and said receiver being mounted in said opening and completely supported by said wall.

9. In a device of the character described, a drum closed at one end and having an opening at its other end, a removable closure for the open end of said drum, a trunnion for journaling said drum rigidly projecting from said closure, a handle for rotating the drum operatively engaged with said trunnion, and a latch bar rotative upon said trunnion between said closure and handle, and coacting with said drum to clamp the closure upon the drum.

10. In a device of the character described, a drum having an opening at one end thereof and formed at said end with an exterior circumferential rib, having a cam face opposing the drum, a closure for said opening removably engageable with the drum, a trunnion centrally carried by said closure for journaling the drum, and a latch bar journaled on said trunnion, extending diametrically of the drum, the ends of said latch bar being hooked to engage the cam face of said rib, whereby rotation of said latch bar is adapted to clamp said closure in its closed position.

In testimony whereof we sign this specification.

JOHN H. GARDNER.
CHARLES A. SAWTELLE.
